DESIGN FOR AN IDENTIFICATION PLATE

George W. Owen, New York, N. Y.

Application May 28, 1938, Serial No. 77,456

Term of patent 7 years

To all whom it may concern:

Be it known that I, George W. Owen, a citizen of the United States, residing at New York, in the county of New York and State of New York, have invented a new, original, and ornamental Design for an Identification Plate, of which the following is a specification, reference being had to the accompanying drawing, forming part thereof.

Fig. 1 is a side view of an identification plate, showing my new design.

Fig. 2 is a front elevation.

Fig. 3 is an end view.

I claim:

The ornamental design for an identification plate, substantially as shown.

GEORGE W. OWEN.
